UNITED STATES PATENT OFFICE.

CHARLES A. LORD, OF LOS ANGELES, CALIFORNIA.

APPARATUS FOR SINKING OIL WELLS.

Application filed June 17, 1924. Serial No. 720,652.

This invention relates to a novel method and apparatus for sinking oil or other wells with expedition, safety, and in an economical manner.

According to the usual practice, it is customary to first dig the well and subsequently put the well casing in place after the drilling or sinking apparatus has been removed, thus necessitating much expensive and often ineffectual precaution against cave-ins and the like between the time the drilling apparatus is removed and the casing is put in place. Furthermore, the usual method of drilling involves many hazards to the equipment as well as the driller, and much of the difficulty is due to the fact that the drilling is accomplished through the medium of a long drill stem to which power is applied at the surface of the ground while the drill itself often works many thousand feet under ground, thereby setting up considerable torque in the drill stem which causes the same to rapidly crystallize and often break off in the well. Also, by this method of drilling it is difficult, if not impossible, to provide a reasonably straight hole due to the flexibility of the drill stem and the encountering of rock or other hard substances by the drill bit, which has a tendency to throw the entire drilling stem off its course thereby producing bends or kinks in the stem which result in a poorly driven well and consequent damage to equipment.

Accordingly, the present invention aims to overcome the difficulties above set forth and at the same time permit of the easy and convenient drilling of the well without waste of equipment and to obtain maximum efficiency throughout all of the operations.

In that connection the invention contemplates placing the well casing in the hole simultaneously with the drilling thereof, yet not in any way interfering with the drilling equipment or imposing unduly the weight of the casing on the drill, whereby the weight of the drill is properly counterbalanced or poised so that it will accurately drill the hole. To that end, the invention contemplates the use of a combined motor and drill unit which digs itself into the ground at the head of a hollow support and in advance of the well casing while the dé-

bris loosened by the bit of the drill will be quickly and automatically removed through the hollow supporting tube by a pump located at the surface of the well.

Another object of the invention is to provide a simple and practical form of drilling unit including a plurality of electrically driven motors arranged in such a manner that they may be successively thrown into operation as more or less power is required to send the apparatus through different strata of sub-soil.

A further novel feature sought by the present construction resides in providing means for properly spacing the drilling unit with reference to the surrounding well casing, a part of said means constituting a washer or plug which seals up the well casing at the desired distance above the casing of the drilling unit so that the suction of the pump at the surface may be readily imposed on the annular chamber surrounding the drill and beneath the washer, thereby to assist in lifting the water and débris around the drill casing and into the débris removing pipe which carries the drill unit.

A still further object is to provide simple and effective means for simultaneously handling the well casing and the débris removing tubing which suspends the drilling unit. That is to say it is proposed to provide novel means at the surface of the well for feeding the well casing down into the hole prepared by the drilling unit, simultaneously with the progress made by the drill while at the same time permitting of the ready attachment of additional well casing sections and additional débris removing pipe sections as the drilling operation proceeds to greater depths.

With the above and other objects in view which will more readily appear as the nature of the invention is better understood, the same consists in the novel construction, combination, and arrangement of parts herein-after more fully described, illustrated and claimed, and in the novel steps of the method set forth in connection with the apparatus referred to.

In the accompanying drawings:
Figures 1 and 1^a show the method employed in the present invention and diagram-

matically represent the apparatus employed to that end.

Figure 2 is an enlarged detail vertical sectional view of the drilling unit.

5 Figure 3 is an enlarged detail view of the collapsible drill bit.

Figure 4 is an enlarged detail sectional view of certain of the teeth on the face of the drill bit.

10 Figure 5 is an enlarged detail view of the section of the well casing where the same engages with the washer or packing ring.

15 Similar reference characters designate corresponding parts throughout the several figures of the drawings.

As previously indicated, the present invention has in view a novel method for simultaneously sinking the well casing with the preparation of the well and to that end

20 it is proposed to employ a novel drilling unit designated generally as A having at the lower end thereof a drill B for digging into the earth and preparing the desired hole to receive the well casing. The drilling unit

25 includes power means for driving the bit and is suspended or carried by a débris removing tube C, the said unit A and the tube C being surrounded by the well casing D. This casing

30 consists of a plurality of pipe sections connected in the usual manner and carried or supported from and at the mouth of the hole, or at the surface of the well, by suitable means for holding, elevating or feeding the casing into the hole according to the re-

35 quirements at each stage of the operation. This means is preferably in the form of anti-slipping rollers E which grip the well casing in such manner as to prevent slipping, there-

40 of but will permit its downward movement as desired by the operator in accordance with the progress of the drilling operation.

As will also be observed from Figure 1, the débris removing tube C which carries the drilling unit A is engaged by the guiding and clutch rollers F which are mounted on slidable carriages G supported by the intermediate platform H. This platform or deck is positioned in the derrick at a suitable distance above the usual floor to provide the necessary clearance to facilitate the placing and connecting of additional well casing sections and additional pipe sections of the débris removing tube. Obviously when it is desired to add additional well

55 casing sections the sliding rollers F-F may be pushed backwardly on their carriages to provide a free passage for mounting the new well casing section on the end of the section about to disappear into the ground.

60 The upper end of the débris removing tube C is formed by a permanent discharge section C' which is provided at its lower end with a suitable coupling C² for connect-

65 ing with the upper end of the last inserted pipe section C³. It will, of course, be under-

stood that each well casing section and also each pipe section of the débris tube C are elevated by suitable block and tackle means not shown thereby to be properly placed one upon the other as each preceding section works its way into the earth. The pipe sections of the débris removing tube are preferably of such length, or may be so manipulated by the operator so as to maintain the relative relation of the joints in the tube C to the joints in the well casing D, as shown in the drawings.

Referring further to the discharge section C' of the débris tube it will be observed that the upper end thereof is preferably provided

80 with a combined suspension hanger and pipe coupling designated generally as I, the same having a bail portion J for cooperating with the hook of a block and tackle device K

85 which not only serves to facilitate the manipulation of the fixed discharge section, but also serves to suspend the entire débris tube C when the device is in use. That is

90 to say, it is not always desirable to impose the entire weight of the column of the tubing C on the drill and for the purpose of regulating the pressure on the drill bit caused by the weight of the tubing, the block and tackle device K may be used.

95 The device I has connected therewith a flexible hose section L which hose is preferably of the same diameter as the tube and connects with a stand pipe M or its equivalent which in turn is connected with a pump N.

100 As will be observed from the drawing the hose L is of sufficient length to compensate for the manipulation of the fixed section C' without disconnecting the hose from either the stand pipe or the discharge section of the débris tube.

105 As will also be observed from Figures 1 and 1^a the space between the débris removing tube C and the well casing D provides for

110 accommodating the water hose line O and the electric cable P both of which are made in sections of suitable length to thereby maintain communication with the drilling unit A at the bottom of the well. The water

115 hose O is connected in any suitable manner with the water supply line O', as for example by a flexible hose O². The water supply line O' may be provided with a suitable valve O³ to shut off the water when a new connection is being made.

120 The power cable P is provided with detachable connections P' and is of course also provided with suitable slack P² connecting with the permanent power line P³, which in turn connects with the controller P⁴ at

125 the operator's control station. The controller P⁴ may be of any conventional type for throwing one or more of the motors of the drilling unit into and out of action as will presently appear.

130 One of the distinctive features of the in-

vention is to provide means to assist the operator in the drilling operation. Thus, the drilling unit A may be equipped with a telephone transmitter T (Fig. 2) suitably carried by the drill casing, the same in turn being connected with a telephone receiving set T' at the surface, the same being equipped with a head set T² for permitting the operator to hear what the drill is doing, thereby indicating whether the drill is passing through soft sub-soil, hard rock or the like. Skilled operators readily become accustomed to the different sounds and can thereby better control the operation and manipulation of the drill accordingly.

As will be observed more particularly from Figure 1^a, the water hose line O as well as the power line P pass through the water plate or gasket U carried by the drill unit A above the cap or cage V which is mounted directly on the drill casing and is provided with openings V' for establishing communication between the interior of the débris removing tube C and the annular space V² provided between the exterior of the casing of the drill unit A and the lower section of the well casing D. The gasket or washer U serves not only to seal the lower end of the well casing from the portion above it, but also serves to center and steady the drill casing A in the lower end of the tube. And, to further assist in centering or steadyng the drill casing, and to prevent canting thereof and a consequently crooked hole, additional spacing means may be used, for example the collar W may be used or suitable lugs may be provided on the inside of the lowermost well casing section as desired.

As will also be seen from Figure 1^a, the lowermost well casing section may be provided with spaced lugs U' for the washer plate U to rest against, thereby having the effect of properly gauging the drill bit with reference to the mouth of the well casing. Also it will be apparent that when the washer plate U rests on the spaced lugs U', the well casing may be automatically propelled or fed into the hole as the drill bit B advances to greater depths. When the drilling unit A thus carries the well casing with it the rollers E—E at the surface of the well merely act as guides and clutch rollers for preventing the casing from falling onto the blades of the bit B. It may be also pointed out that the spaced lugs U' are bevelled on their under sides so as to prevent the blades of the drill from catching theron when the drilling unit is withdrawn, and likewise the spacing of the lugs permits of the spacing and centering collar W to pass by the same without interference. Furthermore, it is to be noted that the lugs U have a relatively limited projection into the tube so as to not interfere with the withdrawal of the drill casing A.

In practicing the present method, the derrick is located at the well site and the preliminary hole for the drilling apparatus is made. Then the first section of the well casing is placed between the rollers E—E 70 which are mounted on the shafts E' which may be connected with any suitable form of braking mechanism and power means for permitting the casing to go into the ground or elevate it as required. In that connection, any of the standard type of well elevator casing mechanisms may be utilized to advantage, however, for the purposes of illustration the rollers E—E have been shown. 75

Within the well casing section is placed the drilling unit A, the same being spaced therefrom by the washer or gasket U and the spacing collar W or its equivalent, with the drill bit B resting upon the ground. The first section of débris removing tubing C 80 having been connected to the upper end of the drilling unit A and the latter in turn having been connected with the permanent discharge section C' of said tubing, the entire device is in condition for operation, assuming, of course, that the proper connections have been made between the water hose O and the source of water supply O' and likewise the proper connection between the power and telephone cable P and the permanent attachment plug P³. The operator may then use the controller P⁴ to control the various motors of the drilling unit A thereby to proceed with the drilling operation. Water being supplied to the drill bit B and the pump end being in operation, the débris worked up by the drill will be removed from the hole by passing around the casing of the drilling unit and thence through the cage V on the top thereof into the débris removing tube C from whence it will be conducted to waste in the usual manner. As the operator permits the drill stem to work its way into the earth, the well casing D is simultaneously permitted to progress into the hole 100 thereby placing the casing, section by section in the hole as the depth increases. When the oil vein is tapped or the oil sands have been reached, the drilling is stopped and the drilling unit A may be readily withdrawn from the well casing due to the automatic collapsing of the drill bit B. In event that the well turns out to be a gusher, the washer or gasket U serves as a stopper or obstruction to prevent unnecessary waste of oil and if desired the débris tube may be used for the purpose of carrying away the oil until opportunity is given to cap the well in accordance with the usual practice preparatory to conveying the oil to suitable reservoirs. 110

Referring more particularly to Figure 2 of the drawings which shows the drilling unit A in detail, it will be observed that the same preferably comprises in its organiza- 120

tion a casing consisting of a body section 1 provided at one end with suitable bearings 2 for receiving the lower end of a combined drill and armature shaft 3 having thereon a plurality of motors 4 each of which is under the direct control of the operator through the controller P⁴ of Figure 1. The armatures of all of the motors 4 are connected directly with the shaft 3 and each superposed motor may be energized by the operator by shifting the handle of the controller, at the surface of the well, as desired, to bring a plurality of motors into play when greater power is required to drill through hard rock or the like.

When the drill bit B strikes a hard stratum of rock it will, of course, require more power to drill through the same, and thus the bringing into play of additional motors 4 will give the desired power to overcome the temporary obstruction encountered by the drill. To assist the drill in the boring operation the combined armature and drill shaft 3 is resiliently mounted in the direction of its axis as will presently appear, and to relieve the shaft of shock due to the blade quickly passing from a soft strata of earth into a hard stratum the shock absorbing spring 5 is provided at the lower end of the column of motors 4.

The upper end of the body section 1 is provided with a bearing plate 6 for receiving the upper end of the armature shaft 3, and to relieve the shaft of undue shock or strain, a shock absorber 7 is provided. The outside of the body 1 is provided at a suitable distance below its upper end with a threaded coupling portion 8 which is adapted to cooperate with a corresponding threaded coupling portion 9 carried by a sealing cap 10 which acts as a cover to seal the upper end of the body 1 of the drill casing. As shown in Figure 2 the exterior threaded parts 8 and 9 cooperate with a coupling ring 11 and a suitable gasket 12 for clamping the cap to the body and providing a water tight joint at that point. The dome 13 of the cap is provided with water tight outlet members 14 and 15 respectively for permitting the entrance of the water hose O into and within the drill casing 1 and the power cable P. The said power cable P connects with a conduit P⁵ which carries the wires P⁶ leading to the various motor units 4.

Referring further to the cap 10 it will be observed that the same is also provided on its side wall adjacent the dome 13 with an externally threaded portion 16 which receives the internally threaded sleeve portion 17 of the cage V previously referred to and which has the openings V'. This cage is provided with a discharge portion 18 which corresponds to the spigot end of a pipe for receiving the bell-end 19 of the lower pipe section of the débris removing tube or con-

duit C. Thus, it will be seen that the entire drilling unit A is carried by and suspended from the débris tubing C.

Referring further to the gasket or washer U it will be observed that the same may be of any suitable and practical construction, and preferably consists of a flange element 20 carried by the cage V, a leather or equivalent flexible washer element 21 and a suitable clamping ring 22 and clamping block 23 held in place by the lower edge of the bell 19 of the lowermost pipe of the débris removing tube. The water pipe O and the power line P pass through the gasket or washer unit U as previously indicated.

The drill bit is shown in detail in Figure 3 and preferably consists of a frame 24 having a central transverse slot 25 in which are mounted the shank portions 26 of a pair of boring blades 27. These blades are pivotally connected as at 28 and the shank portions 26 thereof are provided with arcuate slots 29 which work on pins 30 disposed across the slot 25 in the frame 24. The said blades 27 are provided with relatively flat boring faces 31 having a plurality of staggered teeth 34 which produce in effect the same result as the teeth of a coarse wood file, thereby having the effect of pulverizing hard substances into such a form that they will readily pass out with the water which is used in the boring operation.

As previously indicated the blades 27 are intended to be collapsible, that is, they are intended to recede so as to occupy less space than the diameter of the well casing, thereby to permit the drill bit to be withdrawn from the casing. To that end, the shank portions 26 of the blades are bevelled as indicated at 32 thereby to cooperate with an expanding and releasing cone 33 formed on the end of the combined armature and drill shaft 3. This shaft is provided with a threaded portion 35 cooperating with a similarly threaded portion of the frame 24 so that upon reverse movement of the said shaft the cone 33 will be moved away from the inclined portions 32 of the shanks 26 of the blades which permit the outer edges of the blades to recede. For the purpose of limiting the unthreading movement of the shaft 3 with reference to the frame 24, the same is provided with a reduced neck portion 36 between the cone 33 and the threads 35. This formation provides a lost motion groove for accommodating a stop bar or pin 37 as clearly shown in Figure 3, so that when the motion of the screw is reversed it will not drop the bit frame.

It will be observed that the screw threads 35 are right-hand threads so that the normal turning of the armature shaft 3 will expand the blades 27 to working position. When the drilling unit is to be lifted from the well casing the motors are reversed so that the

threads 35 will unscrew from the frame and release the blades so that they will fall or collapse to a position to permit their withdrawal upwardly through the well casing D.

- 6 From the foregoing it will be apparent that the present invention contemplates a novel method of forming and preparing a well which consists in simultaneously advancing a combined drilling and débris removing unit A, B, C, and the first casing section into the earth, and then progressively adding from the top of the well additional units or sections to the well casing and to the débris conduit as the drilling progresses.
- 10 The drilling unit A is a self-contained power unit having the collapsible drill bit B for advancing into the earth and making a pathway for the casing of the drilling unit as well as the following well casing.
- 15 In connection with the progressive addition of well casing sections and sections for the débris removing conduit it is pointed out that one of the distinctive features of the invention resides in providing a double deck 25 derrick, that is a derrick having a lower platform and an upper platform forming the well casing sections and the sections of the débris removing conduit are respectively handled, thereby making it possible to expeditiously and safely manipulate the well casing and conduit to make it of any length desired.

Another distinctive feature of the invention resides in the provision of the construction involving the combination of the first well casing section and the interiorly spaced drilling unit which is disposed in the mouth of the débris removing conduit, which mouth is provided by the first well casing section.

40 In connection with the removal of material through the conduit C, the particular type of boring blades 27 are an important factor. The relatively short staggered teeth 34 on the faces of the drill blades provide a finely divided earthy mass which finds the water a ready vehicle to facilitate removal.

Without further description, it is thought that the many features and advantages of the invention will be readily apparent to those skilled in the art, and it will, of course, be understood that the changes in the form, proportion and minor details of construction may be resorted to without departing from the spirit of the invention and scope of the appended claims.

I claim:

1. A well making apparatus including in combination, a superstructure, separate platforms at different elevations in said superstructure, a casing, a débris removing tubing, a drilling unit carried by the débris removing tubing, means on said separate platforms for independently sustaining the weight of the débris removing tubing and casing, said means being adapted to progressively lower
- the tubing and also the casing to follow the drilling unit.
2. A well making apparatus including in combination, a superstructure, platforms at different elevations in said superstructure, a casing, a débris removing tubing, a drilling unit carried by the débris removing tubing, means for engaging said tubing mounted on one of said platforms and including parts adjustable at right angles to the tubing, and means on the other of said platforms for sustaining the casing and allowing it to follow the drilling unit.

3. A well making apparatus including in combination, a superstructure, platforms at different elevations in said superstructure, a casing, a débris removing tubing, a drilling unit carried by the débris removing tubing, means on one of said platforms for engaging and feeding said débris removing tubing, means on the other of said platforms for engaging and feeding the well casing, power means and water supplying means carried by the platform which supports the means for engaging the tubing, said power means and water supplying means extending between the casing and the tubing and connecting with the drilling unit.

4. In an apparatus for making oil wells and the like, the combination of well casing sections, tubing sections adapted to form a débris conduit, a drilling unit at the end of said débris conduit, super-structure at the surface of the ground, means carried by said super-structure for separately and simultaneously adding well casing sections and tubing sections to the débris conduit, said means comprising platforms arranged at different elevations, combined guiding, feeding and clutch means on each platform for respectively engaging the sections of the well casing and sections of the tubing of the conduit.

5. In an apparatus for making oil wells and the like, the combination of well casing sections, tubing sections adapted to form a débris conduit, a self-contained power drilling unit carried by the lower section of the tubing constituting the débris conduit and arranged within the well casing, means carried by the conduit adjacent the upper end of the drilling unit and cooperating with a well casing section to provide a débris chamber communicating with the débris tube, means for supplying water to said débris chamber and the drilling unit, a pump connected with the débris conduit, a super-structure, means carried by the super-structure for adding additional well casing sections and additional tubing sections to the débris conduit.

6. In an apparatus for making oil wells and the like, the combination of well casing sections, a self-contained power drilling unit arranged within said well casing sections

- 3 and having a collapsible drill bit arranged in advance of the mouth of the first well casing section, tubing sections forming a débris conduit adapted to be arranged within the 5 well casing sections, means for connecting the lower end of the débris conduit with a drilling unit, said means providing a sealed débris chamber in the lowermost well casing section and establishing communication with 10 the débris conduit, a super-structure at the surface of the ground and means carried by said super-structure for assisting in adding additional well casing sections and additional tubing sections, a pump connected 15 with said débris removing conduit.
7. In an apparatus for making oil wells and the like, the combination of well casing sections, tubing sections arranged within the well casing sections, a self-contained power 20 driven drilling unit arranged within the lowermost well casing section and having a collapsible drill bit arranged in advance of the mouth of such well casing section, means carried by said tubing sections for providing a débris chamber around and about the casing of the drilling unit and means for establishing communication between said chamber and the tubing, a super-structure at the surface of the ground, means for adding 25 sections to the well casing, means for adding sections to the tubing, means for supplying power to the drilling unit, a controller for controlling said power to the drilling unit, means for supplying water to the chamber 30 and drilling unit, a pump connected with the débris tubing, and means for elevating said tubing.
8. In an apparatus for making oil wells and the like, a self-contained power driven drilling unit comprising a casing, a combined drill and armature shaft journaled in said casing, a plurality of motors on said combined armature and drill shaft, a power cable for supplying current to said motors, means for selectively controlling said motors, a drill bit carried by the exposed end of said shaft, a water pipe extending through said casing to supply the drill bit with water, a cap for said casing having fluid tight openings for permitting the passage of the water 40 pipe and the power cable, a suspending cage carried by said cap, and a well casing engaging gasket carried by said cage.
9. In an apparatus for making oil wells and the like, a self-contained power driven drilling unit including a casing, a combined drill and armature shaft journaled in said casing, a drill bit carried by the end of said shaft projecting beyond the casing, a cap for the end of said casing opposite the drill, means for connecting said cap to the casing in a water tight manner, a suspending cage connected with the cap and having openings, and a well casing engaging gasket carried by 45 said cage.
- 50 In testimony whereof I hereunto affix my signature.
- CHARLES A. LORD.
